UNITED STATES PATENT OFFICE.

CHESTER H. BEACH, OF RACINE, WISCONSIN, ASSIGNOR TO FREDERICK J. OSIUS, OF RACINE, WISCONSIN.

SUPPORT FOR SEWING-MACHINE MOTORS.

1,353,211.

Specification of Letters Patent. Patented Sept. 21, 1920.

Application filed November 6, 1916. Serial No. 128,850.

To all whom it may concern:

Be it known that I, CHESTER H. BEACH, a citizen of the United States, residing at Racine, in the county of Racine and State of Wisconsin, have invented a certain new and useful Improvement in Supports for Sewing-Machine Motors, of which the following is a full, clear, concise, and exact description.

10 My invention relates to improvements in supports for sewing machine motors.

In certain types of sewing machines in extensive use at the present time, the machine is closed by swinging the head downwardly into a compartment beneath the level of the table top. The arrangement is so compact that only a little clearance is left between the various parts of the head and the table, as said head is swung through the opening in said table.

20 One object of the present invention is to provide a motor support which shall permit the head of the sewing machine to be swung downwardly beneath the table top without interference from the motor, despite the limited clearance available.

Another object is to provide a motor support which may be attached to the machine by making use of the belt holes in the table 30 top, thereby rendering it unnecessary to make additional holes or in other ways to mar the appearance of said table top, said support permitting the motor to be moved to a position where it will not obstruct the closing of the machine in the usual manner, thereby rendering it unnecessary to remove the motor each time the machine is closed and making said motor practically a permanent part of the machine.

40 A further object is to provide a device of this character wherein the motor may be readily reversed with respect to its support, to permit the same motor to rotate the hand wheel in one direction or the other, depending on the design of the particular sewing machine to which said motor is attached.

Additional objects and advantages may readily be inferred from the more detailed description hereinafter given of the embodiment of the invention illustrated in the drawing.

Figure 1 is a rear elevation of the head of the sewing machine showing the relation of the motor thereto.

Fig. 2 is a section on the line 2—2 of 55 of Fig. 1.

Fig. 3 is a section on the line 3—3 of Fig. 2.

Fig. 4 is a section on the line 4—4 of Fig. 1.

Fig. 5 is an elevation partly in section of certain details of the motor support.

Fig. 6 is a section on the line 6—6 of Fig. 4.

Fig. 7 is a section on the line 7—7 of 65 Fig. 5.

The top of the sewing machine 10, or the table top as it is called, supports a hinged leaf 11 (Fig. 2) on which leaf the sewing machine head, designated as a whole by reference letter 12, is mounted, whereby the head may be swung downwardly to the dotted line position shown in said figure. The head of the sewing machine includes the usual hand wheel 13 and belt pulley 14, 70 the latter being alined with belt holes 15 in the hinged supporting member 11.

The electric motor, by means of which the sewing machine is to be driven, is provided with a base which is preferably L shaped. 80 One arm of the L is composed of telescopic members 16, 17 each provided with a downwardly projecting pin 18 which pin has ridges thereon, giving it a roughened surface adapted to take a firm hold on the wooden support when the device is tightened. Rubber washers 19 are provided to prevent marring of the polished surface of the hinged leaf. The telescoping members and pins constitute a clamp which may be tightened by means of a screw threaded rod 20 having a knurled head 21. Said rod passes through an opening in the closed end 22 of the inner tubular member 16 whereby the inner member may be drawn into the outer member to render the clamp effective. The bottom of the inner tube is flattened and is engaged by the flattened end 23 of the outer tube to prevent relative rotation of these members.

100 The other arm of the L shaped base consists of a rod 24 having a spline groove 25 therein. A sleeve 26 is arranged to slide freely back and forth on said rod and supports a member 27 having a bifurcated lower end provided with openings permitting it to rock about said sleeve. Said member is held in position on said sleeve by screw threaded

collars 28 on opposite sides thereof. To prevent rotation of said sleeve and collars, with respect to said rod, a pin 29 is provided, which fits within the spline groove 25, thereby permitting said sleeve to slide back and forth along the rod 24 without turning. The member 27 may turn about said sleeve through a small angle, its movement being limited by a pin 30 received 10 within a recess 31 in the lower end of the member 27. (Fig. 7).

A suitable spring 32 is provided, to impel the member 27 toward the head of the sewing machine as far as permitted by the pin 30 and slot 31. The spring is preferably 15 a flat spring having its lower end curved about the sleeve 26 and its extremity 33 fitted within a slot in said sleeve. Its upper end presses against the member 27. Said member 27 supports a short bracket 34 the latter being pivoted on the former, having a tongue 35 received within a groove in the upper part of the member 27 and being pivotally connected by a pin 36. As shown in 20 Fig. 1, the bracket 34 cannot be swung beyond a vertical position by reason of the square shoulders 37 on one side of the upper ends of the supporting member 27. The other sides being rounded, however, as shown 25 at 38, said bracket may be swung downwardly approximately to horizontal position. This bracket is locked in vertical position by a spring latch 39 which engages 30 in a recess in the lower end of the tongue 35 (Fig. 4). The bracket may be forcibly moved from its vertical position however, 35 and swung to its horizontal position.

The bracket 34 supports an electric motor 40. This motor may be of any type and 45 construction suitable for the purpose and includes the usual armature shaft 41 having a friction driving wheel 42 thereon which is held in yielding engagement with the hand wheel 13, by means of the spring 32. The driving position of the motor is the 50 one shown in Fig. 1, the base being so designed that when the pins 18 are dropped into the belt holes 15 and the clamp tightened, the motor will be so positioned with 55 respect to the hand wheel that the friction wheel 42 may readily be made to engage said hand wheel. The fact that the sleeve 26 may be slid back and forth along the supporting rod 24, makes it possible to secure 60 the desired frictional engagement of the driving and driven wheels, regardless of slight variations in the location of the hand wheel with respect to the belt pulley. There is considerable variation in this respect in 65 different types of sewing machines and in some cases the belt pulley is on the outside of the hand wheel instead of on the inside thereof.

There is also a variation in the different sewing machines in that in some the hand

wheel rotates in one direction and in the others in the reverse direction. In order to avoid the necessity for reversing the direction of the rotation of the motor, I provide means whereby the motor may be turned 70 with respect to its support thereby permitting it to drive the hand wheel in a reverse direction even though the rotation of the armature with respect to the fields remains unchanged. This turning of the motor is accomplished by removing the pin 36 whereupon the motor supporting bracket 34 and the motor may be turned and remounted on said pin with the armature shaft reversed 75 end for end. The cap 43 which screws into either of the projecting bosses 44 is then removed and the friction pulley 42 also removed from the end of the shaft on which it is located by unscrewing the retaining cap 45 whereupon said pulley may be mounted 80 on the opposite end of the armature shaft and the cap 43 used to cover the opposite projecting end of said shaft.

If the machine were closed in the usual manner, with the motor in its driving position it would not be possible in some types 90 of machines, to completely close the machine and cover the opening through which the head is lowered. To obviate this difficulty, the construction previously described is provided, whereby the motor and its vertical 95 supporting members 27, 34 may first be swung away from the hand wheel through a small arc about the rod 24 as a center, after which the motor may be swung downwardly to the dotted lined position shown in Fig. 1, and if necessary said motor and 100 said supporting members may be slid to the right somewhat along the supporting rod 24. In this position the motor is swung inwardly toward the head of the machine by 105 the spring 32 to the limit of the permissible movement. The head may now be readily lowered in the usual manner, the relative 110 position of said head and motor being shown in dotted lines of Fig. 2.

It will be seen that not only can the machine be closed in the usual way with the supporting structure described, but the motor may be left on the machine as practically 115 a permanent attachment; otherwise it might be necessary to remove the motor every time the machine is closed.

It is obvious that certain features of the invention are capable of use independently 120 of other features and that various modifications may be made in other respects in the structure described herein, without departing from the invention.

Having thus described my invention, what 125 I claim as new and desire to secure as Letters Patent of the United States is:

1. A sewing machine motor support comprising a base having projections fitting 130 within the belt holes and having yielding

- means for holding the motor in frictional driving engagement with the hand wheel. 60
2. A sewing machine motor comprising relatively adjustable members each having a 5 projection received within one of the belt holes and an upwardly extending member arranged to swing about a horizontal axis and normally biased toward the head of the sewing machine. 65
- 10 3. A sewing machine motor support comprising an L shaped base, means on one arm of the L and entering the belt holes of the sewing machine for securing it in place and means on the other arm of said L for pivotally mounting the motor and permitting adjustment of it laterally with respect to the hand wheel. 70
4. A sewing machine motor support comprising a base having means entering both 20 belt holes of the sewing machine, a bracket for the motor, a pivotal connection between the two permitting the motor to be swung from horizontal to vertical position and means permitting movement of said motor 25 toward and away from the sewing machine head. 75
5. A sewing machine motor support comprising a base having means entering both belt holes of the sewing machine, an upright 30 member adjustable back and forth along said base and a motor pedestal pivoted to said upright member. 80
6. A motor support comprising a base having a pair of belt hole engaging projections, a supporting member pivotally mounted thereon and adjustable laterally along the pivotal axis and a motor supporting member pivoted to said first member about an axis at right angles to said first axis. 85
- 40 7. A motor support comprising a horizontal rod, means for supporting the ends of said rod above the table top, said means having a pair of belt hole engaging projections, sleeve slidable on said rod and having 45 non-rotatable engagement therewith, an upright member on said sleeve and a spring associated with said sleeve and said member for impelling the latter toward the sewing machine head. 90
- 50 8. A sewing machine motor support comprising a horizontal splined shaft, a sleeve slidable on said shaft and having means engaging said spline to prevent rotation, an upright member having a bifurcated lower 55 end rotatably mounted on said sleeve, a spring secured to said sleeve and bearing against said member above bifurcated portion, a motor bracket pivoted to said mem- 95
- ber and means for holding said bracket in different positions of adjustment. 100
9. A sewing machine motor support comprising telescoping members each having a pin projecting therefrom at opposite ends, a screw threaded spindle passing loosely through the end of one of said members and having screw threaded engagement with the adjacent end of the other said member and means preventing relative rotation of said members. 105
10. A sewing machine motor base comprising a horizontal supporting rod, a pair of tubular telescopic members arranged at right angles thereto, a roughened pin projecting downwardly from each of said members and rubber pads holding said members and said rods in elevated position. 110
11. The combination with a table top having an opening, of a leaf hinged therein, a sewing machine head supported on said leaf, said head comprising a hand wheel and a belt pulley, a motor base supported on said leaf and held in place by projections received within the belt holes, an upright member pivotally supported on said base, a bracket pivotally secured to said member, a sewing machine motor secured to said bracket, said motor having a friction driving wheel in engagement with said hand wheel, and a spring on said base impelling said motor toward said hand wheel, said upright member 85 and hence said motor being adjustable along said base to bring said friction wheel into and out of the plane of said hand wheel, and said pivoted bracket permitting said motor to be swung downwardly close to said head 90 whereby the sewing machine may be closed 95 without obstruction from said motor. 100
12. The combination with a sewing machine head having a hand wheel, of a motor support having a pair of belt hole engaging projections, a motor mounted thereon, having a friction driving wheel, and means for holding the motor with its driving wheel in yielding engagement with said hand wheel, said motor support comprising two detachable members having pivotal engagement whereby they are permitted relative movement and whereby the motor may be reversed end to end with respect to its support to permit it to rotate said hand wheel 105 110 in either direction.
- In witness whereof I hereunto subscribe my name this 21st day of October, A. D. 1916.

CHESTER H. BEACH.
